UNITED STATES PATENT OFFICE

158,714

HAMPER

Alan Caccia, Philadelphia, Pa.

Application April 27, 1949, Serial No. 2,300

Term of patent 3½ years

(Cl. D58—4)

To all whom it may concern:

Be it known that I, Alan Caccia, a citizen of the United States, residing at Philadelphia, in the county of Philadelphia and State of Pennsylvania, have invented a new, original, and ornamental Design for Hampers, of which the following is a specification, reference being had to the accompanying drawing, forming part hereof.

In the drawing:

Fig. 1 is a front perspective view of a hamper, showing my new design;

Fig. 2 is a front elevational view thereof; and

I claim:

The ornamental design for a hamper, as shown.

ALAN CACCIA.
